TAP CHANGING SWITCH FOR ELECTRICAL APPARATUS

James R. Barr, Rome, Ga., assignor to General Electric Company, a corporation of New York

Filed Mar. 30, 1959, Ser. No. 803,025

13 Claims. (Cl. 200—4)

This invention relates to a tap changing switch for electrical apparatus, and more in particular to an improved no-load tap changer especially adapted for use in changing the taps on a transformer. It will be obvious, of course, that while the following disclosure is directed primarily to the application of the tap changer to a transformer, I do not intend to limit my invention solely to such application.

Transformers, particularly the type that are employed in systems for the transmission and distribution of electrical power, are frequently operated under conditions requiring periodic variation in the voltage ratio of the transformer, and for this purpose the transformers are provided with taps. The taps are connected to suitable switching means so that the number of active turns in the transformer may be varied as desired. The present invention relates to a tap switch suitable for such application. A tap switch may either be designed to vary the ratio of the transformer under load conditions, or it may be a no-load switch that is not intended to interrupt any current. The present invention is intended primarily to provide an improved switch of the latter type, i.e., a no-load tap switch.

Previous no-load tap changing switches of one type have generally been comprised of a plurality of parallel extending cylindrical contact bars uniformly spaced about a common axis and connected to the various taps of the transformer. A movable contact was arranged for rotation about the common axis, and was arranged to selectively bridge adjacent contact bars to provide the desired tap connections. While this arrangement is functionally satisfactory, the mounting arrangements of the components required a relatively expensive structure in order to provide the necessary insulation and mechanical strength, and the circular arrangement of the components required an appreciable mounting space.

As an example of a previous application employing a rotary-type tap changer, a transformer was provided having a secondary winding comprised of two sections with three taps on the end of each section adjacent the other section. In this arrangement, the tap changing switch has six contact bars arranged in a circle, with adjacent contact bars being connected to the tap of opposite sections so that the number of total active turns in the winding would be increased or decreased progressively by rotation of the movable contact. When a rotary-type switch is employed in this type of system, the entire voltage of the tap portions of both sections appears between two of the adjacent rotary contacts, and thus in order to maintain symmetry, the insulation between each pair of adjacent contacts must be sufficient to withstand the voltage of the entire tapped portions of the winding. In addition, the leads connecting the taps of the winding to the contact bars must be well insulated since adjacent taps are connected to opposite sections of the winding. Consequently, the rotary-type of switch has not been found adaptable readily to minimization of space required for the changing of taps.

2

It is therefore, an object of this invention to provide an improved tap changing switch for electrical apparatus.

It is also an object to provide an economical no-load tap changing switch for electrical apparatus requiring less space than the previously disclosed rotary-type.

It is a further object of this invention to provide a no-load tap changing switch especially adapted for transformers and the like, in which the clearance between all adjacent contacts is not dictated by the maximum voltage 10 that may appear between any two contacts.

A still further object of this invention is to provide a no-load tap changing switch for transformers and the like characterized by the fact that it is more economical than previously employed rotary-type switches, does not require as much space as previously employed rotary-types and in which the contact bars are more conveniently arranged for connecting to the taps of the transformer windings.

Briefly stated, in accordance with my invention, I provide a tap changer for electrical apparatus comprising a 20 pair of parallel spaced apart rows of fixed contacts. These contacts have arcuate contacting surfaces, preferably being cylindrical, and are staggered so that the fixed contacts of one row are not in line with the fixed contacts of the other row. Means are provided for selectively bridging between 25 the contacts of the rows comprising an operating means movable between the rows of fixed contacts and parallel thereto. Contact holding means are pivotally mounted on the operating means, and bridging contact means held in the holding means are provided with a pair of arcuate contacting surfaces resiliently urged toward the rows of contacts.

While the specification concludes with claims particularly pointing out and distinctly claiming the subject matter which I regard as my invention, it is believed that the 35 invention will be better understood from the following description taken in connection with the accompanying drawing.

In the drawing:

Fig. 1 is a perspective view of a tap changing switch according to one embodiment of my invention, and illustrating the switch in one position.

Fig. 2 is an enlarged cross-sectional view of the bridging contact arrangement of the tap changing switch of Fig. 1.

Fig. 3 is a perspective view of the bridging contact arrangement of Fig. 2.

Fig. 4 is a top view of a contact and a portion of the bridging contact assembly of the switch of Fig. 1, and illustrating the electrical contact between these members.

Fig. 5 is a side view illustrating a portion of the switch 50 of Fig. 1 in an intermediate position.

Fig. 6 is a perspective view of a portion of the switch of Fig. 1 illustrating the bridging contact in an intermediate position, and

Fig. 7 is a circuit diagram illustrating a typical application of the tap changing switch of Fig. 1 as connected to the windings of a three-phase transformer.

Referring now to the drawing, and more in particular to Fig. 1, therein is illustrated a tap changing switch comprising a plurality of fixed contacts mounted on a rigid insulating panel 10. The contacts are disposed in two parallel rows, for example, with contacts 11, 12 and 13 comprising one row of contacts, and contacts 14, 15 and 16 comprising the other row of contacts. The six contacts 11 through 16 are preferably cylindrical and extend in parallel relationship with each other, preferably perpendicularly to the panel 10. The six contacts 11 through 16 are also staggered so that a perpendicular line joining a contact of one row would cross the other row at a point equidistant between two contacts of the other row. For example, a perpendicular line extending from the contact 14, to the row of contacts 11, 12 and 13, would cross the row of contacts 15 and 16 at a point equidistant between the contacts 15 and 16. The contacts 11 through 16 are also staggered so that a perpendicular line joining a contact of one row would cross the other row at a point equidistant between two contacts of the other row. For example, a perpendicular line extending from the contact 14, to the row of contacts 11, 12 and 13, would cross the row of contacts 15 and 16 at a point equidistant between the contacts 15 and 16.

tacts including contacts 11, 12 and 13, would cross the latter row at a point equidistant between the contacts 11 and 12.

While the illustration of Fig. 1 shows a tap changing switch employing only three fixed contacts in each row, it will be obvious that any number of such contacts may be employed without departing from the spirit or scope of my invention.

A movable contact for bridging the fixed contacts of the two rows is provided comprised of a contact holding member 20, one movable contact 21 adapted to contact the fixed contacts of the row including fixed contacts 11, 12, and 13, and another movable contact 22 adapted to contact the fixed contacts of the row including contacts 14, 15 and 16. As may be more clearly seen in Fig. 2, the contact holding member 20 may be a tubular metallic member in which an outer tubular contact holder 23 is slidably mounted. An inner tubular contact holder 24 is slidably mounted in the outer contact holder 23. The outer contact holder 23 extends beyond the contact holding member 20 at one end thereof, where it is rigidly fastened to the movable contact 22. Similarly, the inner contact holder 24 extends beyond the other end of the contact holding member 20, where it is rigidly fastened to the other contact 21. A helical spring 25 is provided within the inner contact holder 24, the spring 25 biasing both of the movable contacts 21 and 22, along with their tubular holders 24 and 23 respectively, outwardly of the contact holding member 20. Means such as a screw 26 threaded to the wall of the contact holding member 20, is provided to limit the inwardly and outwardly movement of the movable contacts, such as by engaging slots 27 and 28 in the walls of the tubular contact holders 23 and 24 respectively. In order to assure electrical contact between movable contacts, a flexible conductor, such as a braid conductor 29 may be provided extending between the contacts 21 and 22 within the helical spring 25.

The contacts 21 and 22, which may be more clearly seen in Fig. 3, are provided with arcuate portions 30 joined on either side by inclined portions 31. The inclined portions 31 may also be tapered, as shown in Fig. 3. As illustrated in Fig. 4, the arcuate surface 30 has a radius of curvature slightly less than that of the fixed contacts such as the contact 13, so that the movable contact 21 contacts the fixed contact 13 only at the lines of junction 32 between the arcuate surfaces 30 and the inclined surfaces 31. This arrangement assures two spaced apart line or point contacts between the moving and fixed contacts, and is therefore preferred to the arrangement in which the contacts have the same shape, since the latter type electrical contact may be established at only one point.

Referring now to Fig. 5, the contact holding member 20 is provided with a pair of pins 35 extending normal to the axis of the member 20 and on opposite sides of the member 20. The pins 35 extend through slots 36 in parallel extending plates 37 (see also Fig. 1). The ends of the plates 37 are bolted or otherwise rigidly affixed to insulating bars 38 extending in opposite directions from the movable contact assembly. The bars 38 extend parallel to the rows of fixed contacts, and substantially intermediate the rows of contacts. Axially extending slots 39 are provided in the bars 38, and the bars 38 are supported for axial movement between the fixed rows of contacts by bolts 40 extending through the slots 39 to the panel 10. Spacers 41 may be provided surrounding the bolts 40 between the panel 10 and insulating bars 38 to space the bars 38 from the panel. In order to provide sufficient clearance between the plates 37 for the moving contact assembly, spacers 42 may also be provided between the plates 37 and the bars 38 surrounding the bolts holding the plates 37 to the insulating bars.

Referring again to Fig. 1, the moving contact assembly is therein illustrated bridging the fixed contacts 13 and 16. The ends of the insulating bars 38 toward

the moving contact assembly are spaced apart sufficiently that they do not interfere with the movable contact assembly when the movable assembly is bridging contacts between the two rows. As will be disclosed in more detail in the following paragraphs the ends of the insulating bars 38 must also be sufficiently close that they will be able to nudge the movable contacts from engagement with the fixed contacts before axial force on the bars 38 is transmitted to the movable contact assembly by way of the slots 36. Thus, assuming that a vertical upward force were applied to the insulating bars 38 in the arrangement of Fig. 1, the upper end 50 of the lower insulating bar would contact the movable contact 22 to nudge it slightly from engagement with the fixed contact 16 before the lower end of the slot 36 engages the pins 35. Any suitable operating mechanism may be provided for moving the insulating bars 38 axially.

In the arrangement of Fig. 1, the moving contact assembly bridges the fixed contacts 13 and 16, with the movable contact 21 contacting fixed contact 13, and movable contact 22 contacting fixed contact 16. If it is now desired to move the movable contact assembly so that it bridges the fixed contacts 13 and 15 an upward force is applied to either of the insulating bars 38. Reference to an upward direction, is of course purely descriptive to facilitate the description of the operation of the mechanism as disclosed in Fig. 1, since the tap changing mechanism of my invention may be disposed at any angular position. The initial upward movement of the insulating bar 38 will not result in any movement of the movable contact assembly, until the upper end 50 on the lower insulating bar engages the movable contact 22. At the time that the end 50 engages the contact 22, the upward movement of the bar 38 has not resulted in engagement between the bottom of the slot 36 and the pin 35, so that the lower plate 50 nudges the contact 22 upwardly. This results in the compression of the spring 25 within the movable contact assembly, to permit the upward movement of the contact 22. After the contact 22 has moved sufficiently upwardly, the lower inclined surface 31 of the contact 22 engages the fixed contact 16 and the contact 22 is free to move out of engagement with the fixed contact 16, upon further upward movement of the insulating bars 38. After the contacting surface of movable contact 22 has moved out of engagement with the fixed contact 16, the lower end of the slot 36 engages the pin 35, so that further upward movement of the insulating bars 38 results in the pivoting of the movable contact assembly about the axis of the fixed contact 13. This pivotal movement continues, with further upward movement of the bars 38, until the upper inclined surface 31 of the contact 22 engages the next adjacent contact 15, as illustrated in Fig. 6. The contact between the upward inclined surface of the movable contact 22 and the fixed contact 15 results in the depression of the spring 25, which permits the contact 22 to snap into full contacting engagement with the fixed contact 15. This snap action permits minor errors in alignment between individual tap selectors when several selectors are operated from a common control, and also permits minor errors in indexing of the operating mechanism for the selectors.

The above disclosed arrangement including the slots 36 and plates 50 have been provided in order to assure the release of the correct movable contact upon the application of force to the insulating bars. Thus, for example, if a simple pivot were provided for the pins 35, it would be possible that upward force on the bars 38 would result in the release of the movable contact 21 rather than the movable contact 22. Such a condition could occur as a result of unequal friction within the movable contact assembly or between the fixed and movable contacts. In the arrangement of Fig. 1, however, the desired movable contact is nudged out of contact relationship with the fixed contact before the application of force,

by way of the pins 35, to the other movable contact. Further, in the arrangement of Fig. 1, if the movable contact 21 should accidentally move upwardly before the contact 22 is moved, it would strike the upper plate 50, which would prevent its release.

Referring now to Fig. 7, which illustrates a typical application of the tap changer of Fig. 1, a three-phase transformer is provided having parallel insulating cylinders 60, 61 and 62. Each of the insulating cylinders is provided with a winding having an upper portion 63 of a plurality of turns separated from a lower portion 64 of a plurality of turns. The insulating cylinders 60, 61 and 62 may surround the winding legs of a magnetic core (not shown) according to conventional practice, and other windings (not shown) may also be employed inductively coupled to the winding groups 63 and 64. A tap changing device of the type illustrated in Fig. 1 is mounted on each winding cylinder between the upper and lower groups of windings 63 and 64, with the panels 10 lying in a vertical plane and the axes of the insulating bars 38 being horizontal. All of the panels 10 lie in the same plane, and the insulating bars 38 of adjacent switches may be joined as illustrated in Fig. 7. The insulating panels 10 may be spaced from their respective winding cylinders to permit connection of tap leads to the undersides of the panels, and any suitable support structure may be provided for rigidly holding the tap switches in place. A rack 66 may be provided on the extremities of one of the insulating bars 38, and a pinion gear 67 engages the rack to translate rotary motion of a suitable tap operating means 68 by way of a gear box 69 if desired, to axial movement of all of the insulating bars 38 and hence the movable contact assemblies.

The lower end 70 of each upper winding group 63 is connected to the fixed contact 14, of the respective switch 35 and similarly the upper end 71 of each lower winding group 64 is connected to the fixed contact 11. A tap 72 of each upper winding group is connected to the fixed contact 16 and a corresponding tap 73 on each lower winding group is connected to the fixed contact 13. An intermediate tap 74 on each upper winding group is connected to the intermediate fixed contact 15 on the upper row of contacts, and similarly an intermediate tap 75 on each lower winding group is connected to the intermediate fixed contact 12. With this arrangement, when the movable contact bridges the contacts 11 and 14, the maximum number of turns will appear between the upper terminal 80 of each winding group 63 and the lower terminal 81 of each winding group 64. When contact is made between the fixed contacts 12 and 14, the total number of turns between the winding terminals 80 and 81 is reduced by the number of turns appearing between the end 71 of the winding group 64 and the intermediate tap 75 of the winding group 64. When the movable contact assembly bridges the contacts 15 and 12, the total number of turns between terminal 80 and 81 is further reduced by the number of turns between the lower end 70 of the upper winding group and the intermediate tap 74 of the upper winding group. When the movable contact assembly bridges the fixed contacts 13 and 15, the number of active turns between the terminals 80 and 81 is still further reduced by the number of turns between the taps 75 and 73 of the lower winding group, and when contacts 13 and 16 are bridged, the minimum number of turns appears between the terminals 80 and 81.

In the arrangement of Fig. 7, it is to be noted that the fixed contacts of each row of the tap changing switch are connected to the same winding group, so that the necessary insulation between adjacent contacts in each row is determined only by the voltage between adjacent taps of the winding. While the rows of contacts must be separated sufficiently to withstand the voltage of the sum of the tapped groups, the necessary spacing to provide such insulation is normally no greater than the space required for the moving contact assembly. In ad-

dition, Fig. 7 illustrates that the tap changing switch of my invention may be conveniently placed adjacent the ends of the winding groups of a transformer without the necessity for heavily insulating the tapped leads, since adjacent contacts in each row of fixed contacts are all connected to the same winding group. Thus with this arrangement the tap leads may be very short and still be physically separated so that they require little or no insulation. The tap leads may be sufficiently short that they are self supporting.

When the tap changing switch of my invention is employed as illustrated in Fig. 7, tap changes may be made simultaneously on each of the switches of a three-phase transformer by the use of a simple hand crank connected to the bar of one of the switches. The assembly also requires a minimum space since the dimension of the switches radially of the windings is minimized and no complex connecting system is required between the adjacent tap changing switches.

It will be understood, of course, that, while the form of my invention herein shown and described constitutes the preferred embodiment of my invention, it is not intended herein to illustrate all of the possible equivalent forms or ramifications thereof. It will also be understood that the words employed are words of description rather than of limitation, and that various changes may be made without departing from the spirit or scope of the invention herein disclosed, and it is aimed in the appended claims to cover all such changes as fall within the true spirit and scope of the invention.

What I claim as new and desire to secure by Letters Patent of the United States is:

1. A tap changer for electrical apparatus comprising a pair of parallel spaced apart rows of staggered fixed contacts, and means for selectively bridging between the contacts of said rows comprising operating means movable between said rows in parallel relation thereto, contact holding means pivotally mounted on said operating means, and bridging contacting means held in said holding means and having contact surfaces resiliently urged toward said rows.

2. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising operating means movable parallel to said contact rows and between said rows, contact holding means pivotally mounted on said operating means, and first and second bridging contacts held by said holding means and resiliently urged towards said first and second rows respectively.

3. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising operating means disposed between said rows of contacts and adapted for linear movement parallel to said rows, contact holding means pivotally mounted on said operating means on an axis parallel to the axes of said fixed contacts and equal distance from said rows, and first and second bridging contacts held by said holding means and resiliently urged towards said first and second rows respectively.

4. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising operating means disposed between said rows and adapted for linear movement parallel to said

rows in a plane normal to the axes of said fixed contacts, contact holding means pivotally mounted about an axis parallel to the axes of said fixed contacts and equal distance from said rows, and first and second bridging contacts having accurate contacting surfaces, said bridging contacts being held by said holding means and being resiliently urged toward contacting relationship with the contacts of said first and second rows respectively.

5. The tap changer of claim 4 in which the radius of curvature of the accurate contacting surfaces of said bridging contacts is smaller than the radius of curvature of said fixed cylindrical contacts.

6. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising operating means disposed between said rows and adapted for linear movement parallel to said rows in a plane normal to the axes of said fixed contacts, contact holding means pivoted about an axis parallel to the axes of said fixed contacts and equal distance from said rows, first and second bridging contacts held by said holding means and resiliently urged toward said first and second rows respectively, said holding means being pivoted in slots in said operating means, and means for urging said bridging contacts from contacting relationship with said fixed contacts upon movement of said operating means before movement is transmitted to said holding means by way of said slots.

7. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising operating means disposed between said rows and adapted for linear movement parallel to said rows contact holding means pivoted in slots in said operating means about an axis parallel to the axes of said fixed contacts, said slots extending parallel to said rows, first and second bridging contacts held by said holding means and resiliently urged toward said first and second rows respectively, and means for urging said bridging contacts from contacting relationship with said fixed contacts upon movement of said operating means before movement is transmitted to said holding means by way of said slots.

8. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising insulating shaft means disposed between said rows and adapted for linear movement parallel to said rows, parallel spaced apart slotted members affixed to said shaft means for movement therewith, slots in said parallel members, contact holding means pivotally mounted in said slots about an axis parallel to the axes of said fixed contacts, first and second bridging contacts held by said holding means and resiliently urged toward said first and second rows respectively, and means on said insulating shaft adapted to selectively engage said bridging contacts to urge them from contacting relationship with fixed contacts upon movement of said insulating shaft before movement is transmitted to said holding means by way of said slots.

9. A tap changer for electrical apparatus comprising first and second parallel spaced apart rows of staggered parallel extending fixed cylindrical contacts adapted to be connected to said apparatus, and movable contact means for selectively connecting one contact of said first row to one contact of said second row, said movable contact means comprising insulating shaft means disposed between said rows adapted for linear movement parallel to said rows in a plane normal to the axes of said fixed contacts, parallel pivot plate members affixed to said insulating shaft means for movement therewith, said pivot plate means being spaced apart and having slots extending thereto, contact holding means pivotally mounted in said slots about an axis parallel to the axes of said affixed contacts an equal distance from said rows, first and second bridging contacts held by said holding means and resiliently urged toward said first and second rows respectively, and means affixed to said insulating shaft means and adapted to selectively engage said bridging contacts to nudge them from contacting relationship with said fixed contacts upon movement of said insulating shaft means before movement of said shaft means is transmitted to said holding means by way of said slots.

10. A tap changer for electrical apparatus comprising an insulating panel, first and second parallel spaced apart rows of staggered cylindrical contacts affixed to said panel and extending normal thereto, said contacts being adapted to be connected to said apparatus, and movable contact means for selectively connecting one contact of said first row to one contact of said second row, said movable contact means comprising operating shaft means disposed between said rows and adapted for linear movement parallel to said rows in a plane parallel to said panel, holding means, means affixed to said insulating shaft means for loosely pivotally holding said holding means on a pivotal axis parallel to the axes of said fixed contacts an equal distance from said rows, first and second bridging contacts having arcuate contacting surfaces, said bridging contacts being held by said holding means and being resiliently urged toward contacting relationship with the contacts of first and second rows respectively, and means affixed to said insulating shaft means and adapted to engage said bridging contacts selectively to urge them from contacting relationship with the contacts of first and second rows upon movement of said insulating shaft means before movement is transmitted to said holding means by way of said pivotal axis.

11. The tap changer of claim 10 in which the radius of curvature of the arcuate contacting surfaces of said bridging contacts is less than the radius of said cylindrical contacts.

12. The tap changer of claim 10 in which spring means are provided in said holding means to urge said bridging contact toward contacting relationship with said cylindrical contacts.

13. The tap changer of claim 12 in which inclined contacting surfaces are provided on each side of the arcuate contacting surfaces of said bridging contacts, such that said spring means is depressed before and after said arcuate contacting surfaces of said bridging contacts engage said fixed contacts.
